CLAIM

The ornamental design for a dough press, as shown and described.

DESCRIPTION

FIG. 1 is a front, right-side, and top perspective view of a dough press showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a sectional view thereof taken along line 8-8 in FIG. 6.

The dashed broken lines depict portions of the dough press in which the design is embodied that form no part of the claimed design.

The dot-dash broken lines show the cross sectional line for FIG. 8 in FIG. 6 and form no part of the claimed design.
